ATT'Y

UNITED STATES PATENT OFFICE.

PETER FORG, OF SOMERVILLE, MASSACHUSETTS.

DESIGN FOR A SPROCKET-WHEEL.

SPECIFICATION forming part of Design No. 29,524, dated October 18, 1898.

Application filed July 30, 1898. Serial No. 687,363. Term of patent 7 years.

To all whom it may concern:

Be it known that I, PETER FORG, a citizen of the United States, residing in Somerville, in the county of Middlesex and State of Massachusetts, have invented and produced a new and original Design for Sprocket-Wheels, of which the following description, in connection with the accompanying drawings, is a specification, like letters on the drawings representing like parts.

The design relates to a sprocket-wheel for bicycles; and it consists in a sprocket-wheel distinguished by its peculiar shape, as will be hereinafter set forth and claimed.

Figure 1 is a front elevation of a sprocket-wheel embodying this design; and Fig. 2, a section on the line 2 2, Fig. 1.

The leading and distinguishing feature of my design, as shown in the drawings, consists

of a large central star *a*, having its points connected together by a circular ring *b*, from which project outwardly smaller stars *c* and bars *d*, representing stripes, which are united by a larger concentric ring *e*, from which project outwardly the teeth *f*.

This design is embodied in a sprocket wheel in which the points of the large central star *a* are united to the ring *b* by curved bars *g*.

I claim

The design for a sprocket-wheel herein shown and described.

In testimony whereof I have signed my name to this specification in the presence of two subscribing witnesses.

PETER FORG.

Witnesses:

JAS. H. CHURCHILL,
J. MURPHY.
